UNITED STATES PATENT OFFICE.

WILLIAM H. WINSLOW, OF CHICAGO, ILLINOIS, ASSIGNOR TO WINSLOW SAFETY HIGH-PRESSURE BOILER COMPANY, OF CHICAGO, ILLINOIS, A CORPORATION OF ILLINOIS.

STEAM-BOILER.

1,236,641.

Specification of Letters Patent. Patented Aug. 14, 1917.

Application filed May 28, 1914. Serial No. 841,445.

To all whom it may concern:

Be it known that I, WILLIAM H. WINSLOW, a citizen of the United States, residing at Chicago, in the county of Cook and State of Illinois, have invented a certain new and useful Improvement in Steam-Boilers, of which the following is a full, clear, concise, and exact description, reference being had to the accompanying drawings, forming 10 a part of this specification.

This invention relates to steam boilers.

The efficiency of a steam plant involves the combined efficiencies of the two main parts of such a plant, namely, the boiler and 15 the engine.

The inherent efficiency of the engine depends upon the temperature range of the motive fluid employed in accordance with the well known formula,

$$20 \quad \text{Efficiency} = \frac{T^1 - T^2}{T^1},$$

in which T^1 represents the initial temperature and T^2 represents the exhaust or final 25 temperature. The lower limit of the temperature range T^2 is practically fixed by the temperature of the atmosphere or of the condensing water and increase of inherent efficiency is limited to the sole possibility of 30 using a higher initial temperature T^1 of the motive fluid.

Inasmuch as it is the duty of the boiler to furnish the steam or other motive fluid, any increase in initial temperature T^1 requires extra duty from the boiler as the temperature of saturated steam is directly linked 35 with the pressure. So great difficulty has been experienced in the past in raising the temperature of the steam to any considerable 40 degree because of the increased pressure, that mechanical strength has become the limiting factor in modern boiler construction.

In an attempt to secure a boiler structure 45 capable of furnishing high pressure high temperature steam, the flash boiler was developed. This type of boiler is not available for furnishing large quantities of steam, and so extremely difficult of regulation that 50 it is impractical. Hence, this type of boiler has failed to furnish a satisfactory solution of the problem.

In the equation of a gas $PV = RT$ where 55 P is absolute pressure, V is volume, T is absolute temperature and R is the constant.

of the gas employed, it can at once be seen that the temperature T may be raised without increasing the pressure P by increasing the volume V .

Knowledge of this property has led to 60 the modern practice of superheating the steam as it passes from the boiler to the engine.

But again, mechanical strength of the boiler or of the superheating unit has become the limiting factor.

It has been found impossible in commercial boilers of the type generally used heretofore to obtain superheating for two chief reasons: First, in commercial boilers the 70 steam remains in contact with a large surface of water from which wet steam is constantly given off and superheating under these conditions is out of the question; second, the said type of boiler will be "burned" 75 and will be opened at the seams if the temperature requisite to superheating be applied to any part of the boiler not covered by water.

The best modern practice prior to my invention has been the provision of a separate superheater but the separate superheater is subject to numerous defects and it is difficult to keep it in operation. One grave danger is the tendency to "burn" when the 80 flow of steam ceases or is reduced to any considerable extent because of the small steam content and the consequent small thermal capacity. If the capacity be made great enough to properly superheat the 90 steam without burning, the superheater becomes almost as extensive as a boiler itself.

Another difficulty in the use of superheaters of the prior art is the tendency to burn out while the boiler is being brought 95 to the proper temperature for service. This has necessitated means for charging them with water or of screening them off from the furnace during the period of getting up steam.

Another danger is that the seams of the superheater will be started in case a slug of water be drawn into the superheater.

The present invention relates particularly to a boiler for delivering high pressure superheated steam.

The chief object of the invention is to provide a boiler of maximum mechanical strength capable of supplying superheated steam at high pressure.

100

105

110

Another object is to provide a boiler with a superheater of maximum inherent thermal and mechanical efficiency.

Another object of the invention is to provide a furnace of improved construction for realizing to the greatest extent the mechanical and thermal advantages of the above mentioned boiler.

Another object of the invention is to provide an improved process of generating steam.

Another object is to provide a boiler structure having the advantages of rapid circulation and steaming ability.

Another object is to provide a single unitary boiler structure in which distinctly different zones of thermal action are continuously carried on.

I have found that the proper design of a high pressure boiler is controlled largely by the requirement for strength. Thermal efficiency and mechanical efficiency must also be satisfied but the requirement for strength is the basic requirement. The particular boiler which is illustrated in the accompanying drawings is adapted to carry in practice, pressures of the order of 500 pounds to the square inch. This boiler is characterized by a construction involving the use of tubes of relatively small diameter only. There is a complete absence of large drums or containers under pressure.

Mechanical efficiency in the design of a high pressure boiler further requires substantially uniform construction throughout the parts of the boiler which are under pressure. The thickness of material employed throughout must be substantially uniform due to the thermal coefficient of expansion. The thickness must be great enough to sustain the pressure upon the receptacle with the required degree of safety but the thickness of the parts must not be excessive if an efficient transfer of heat through the walls of the container is to be effected. The boiler should be constructed of wrought metal. It is the only material having sufficient strength to stand the pressure under the conditions of use to which the tubes are put. The joining of wrought metal tubes and cast metal headers produces joints which will open under conditions of use. Cast metal will crack under continued heat and pressure. Mechanical efficiency demands a structure of wrought metal for the parts subjected to heat and pressure.

It is therefore imperative that the receptacle be built up of wrought metal tubes of relatively small diameter having thin walls if high pressures are to be safely carried and mechanical efficiency and thermal efficiency are taken account of.

In the practice of my invention, I employ a boiler comprising sections of unitary integral construction formed by autogenous

welding of the general type disclosed in my copending application, Serial No. 656,179.

This application is for an improvement upon the boiler described in the above application and for certain purposes is a continuation, thereof.

In the drawings—

Figure 1 is a schematic illustration of the action occurring in the boiler when the same is steaming;

Fig. 2 is a vertical longitudinal cross-section of a boiler and furnace embodying the present invention; and

Fig. 3 is a plan view of the boiler elements shown in Fig. 2 with the casing removed and the steam header bent to one side to expose the connection of this header with the risers.

The boiler shown in Figs. 2 and 3 consists essentially of a number of units or sections, each of which is built up of risers 1 and 2, and a plurality of connecting tubes 3 secured preferably by autogenous welding to the risers 1, 2.

The riser 1 is made shorter than the riser 2 and the tubes connecting these risers are placed at different inclinations at various points of the unit. At the top of the unit the tubes are substantially level.

At the bottom of the unit the tubes are inclined from the shorter riser down to the bottom of the longer riser. The tubes intermediate have various inclinations in substantially regular order approaching the level position at the top of the section. Each one of the tubes 3 is welded to the headers and in this manner the section becomes one integral piece of metal of great strength. In practice I prefer to form the lower tubes with a slight curvature or bowing to provide for the effect of expansion by heat.

At the top of the riser 2 of each section, a steam connection 4 joins the unit to the steam header 5. This header 5 contains an equalizing pipe 6 for equalizing the steam drawn from the various sections when the boiler is in operation. This pipe has a number of apertures 7 adjacent the connections 4 to the various units. The total cross section of the apertures 7 is greater than that of the steam pipe 8 leading to the engine, but the size of the individual apertures is such that considerable resistance would be offered to the passage of more than a certain amount of steam such as might occur if the sections were worked unequally.

At the bottom of the header 2 a mud drum 10 allows any sediment or scale to collect. The boiler may be cleaned by opening the blow-off cock 11 connected to the mud drum 10 in a well known manner.

A cold water supply pipe 12 has connections 13 leading to the various units of the boiler to supply feed water to the units.

The boiler is inclosed in a casing or setting 15 which may be made of any suitable material, preferably of fire brick, or the like.

5 A fire box 16 is inclosed in this casing under one end of the sections and a smoke flue 17 connects with the casing at the rear of the boiler.

10 The top or roof of the boiler casing is supported by a number of girders or steel beams 20. These beams may be protected by refractory material or may be left exposed, as preferred. A plate 21 resting upon the top of the front wall of the casing 15 supports the forward end of the boiler sections by means of rods 22 connected to the headers 1 of the different sections.

15 A suitable coping 23 of ornamental design may be placed on the roof of the boiler casing to give a finished appearance.

20 The smoke flue 17 opens into a stack 18. The back of this flue contains a number of doors 19 which may be opened for inspecting the boiler or for removal of a section, if the same is found necessary. To remove a section it is necessary only to open the door 19 to disconnect the section from the steam header 5, the feed pipe 12 and the mud drum 10 by means of unions provided in each connection to disconnect the rod 22 at the front of the section, and the same may be readily withdrawn by means of the loops or handles 24 provided on the back of each section.

25 The fire box 16 may contain grates 30 for burning coal or other solid fuel, or the same may contain a gas or oil burner of any preferred design. I consider each form of heater to be equally well suited to heat a boiler and, hence, have illustrated only the grates for burning coal, or the like.

The front wall 31 of the fire box contains the opening 32 closed by the fire door 33.

30 An ash pit 35 beneath the grate 30 is rendered accessible by means of the opening 36 closed by the ash door 37.

35 The rear of the fire box 16 is formed by the wall 40 which is extended as a baffle plate 41 up through the tubes of the boiler. 40 The baffle 41 may be constructed of separate parts attached to the tubes so that, when a boiler section is removed, the section of the baffle attached thereto will be removed simultaneously. Supports 43 may be employed to bear the weight of the section when the suspension means 22 is released, but ordinarily the weight of each section is carried by the corresponding rod 22 and by the pillow block 9 beneath the mud drum 10.

45 As will be seen in Fig. 3, the risers 1 are placed contiguous to each other and form practically a solid wall, as viewed from the front of the boiler. In the same manner, the risers 2 present practically a solid wall 50 to the rear of the boiler. This is important

as these risers tend to define part of the fire flue and smoke flue space of the furnace. The fire flue space 44 is provided between the front wall of the boiler casing 15 and the risers 1 to conduct the hot gases to the top of the boiler sections. A space 45 is formed above the boiler sections between the roof of the shell and the uppermost tubes and this space is in connection with the flue 44. No direct connection is afforded with the smoke flue 17, however, as the space 45 is closed at the rear part by plate 46 in contact with the risers 2 at the rear of the sections. A damper 47 controlled by handle 48 is located at the top of the flue space 44 in order to regulate the amount of hot gas that passes through this space. Assuming that there

is a fire on the grates 30, part of the products of combustion will rise directly through the nest of tubes over the baffle 41 and will then pass down between the baffle 41 and the risers 2, which, as above explained, form practically a solid wall, thence, down into the smoke box 50, and out to the stack 18 by means of the smoke flue space 17. It will be

50 noticed that the headers in this case define the path of movement of the hot gases, that the course of the gases, as above set out, is first up through the tubes, down through the tubes between the baffle and the rear header, and up and out along the rear header. An

55 other and minor part of the hot gases is allowed to pass up through the flue space 44 and over the tops of the sections, through the uppermost tubes above the baffle 41, thence, down between the baffle 41 and the rear headers 2 and out in the same manner as described above. It will be noticed that

55 these gases on their upward movement are in contact with the header 1, but otherwise are led directly to the top of the boiler and there impinge upon the uppermost tubes of the sections. Each path for gases contains

60 a first pass of the gases from the furnace through all or substantially all of the tubes regardless of the water level. The smoke box 50 may be provided with a door 51 for the withdrawal of soot and cinders.

65 The general proportions of the boiler are substantially different from prior art devices in that the sections are relatively high in the vertical dimensions and relatively short in the fore and aft dimensions. This secures beneficial results in a number of ways. It permits of relatively greater variation of water level. It provides a more rapid circulation of the water. It provides freedom from priming upon sudden demand for steam. It also provides a more compact and economical structure.

70 The operation of the boiler will now be briefly set forth, especially in connection with the diagram of Fig. 1.

75 Fig. 1 is a diagram for explaining the action of the boiler and is not meant to dis-

70

close structure. In other words, the structure of the mechanism shown in Fig. 1 is purely imaginary and does not exist in practice, but has been shown merely to make clear what goes on in the boiler when the boiler is steaming. The operation described in connection with the diagram of Fig. 1 is the operation that goes on in the actual structure and, although the structure of Fig. 1 is fictitious, the description of operation in connection with Fig. 1 is representative of the true action of the boiler. Let it be assumed that the uppermost tubes, which are practically level, are grouped and united into one single tube which performs the function and takes the place of all the separate tubes of that group. The intermediate tubes are assumed to be grouped into a single tube as their action may well be illustrated by the action of a single tube but the lowermost group of tubes is represented by a pair of tubes in which circulation of the water is carried on. We have then, as illustrated in Fig. 1, the headers 1 and 2 connected by four tubes which represent three groups of tubes. The boiler is not completely filled with water, but only partially filled, somewhat as indicated by Fig. 1. A definite level is not imperative as this may vary to a considerable degree without affecting the working of the boiler. As indicated by the arrows extending from the fire box, Fig. 1, there are two main paths for the hot gases, one along the side of the header 1 and down through the tubes beneath the header 2 and out along the sides of header 2, the other path being traced up through the tubes to a point near the upper group of tubes down through the rear part of the tubes and up to the stack along the header 2, as in the first path.

Both currents of gases tend to heat intensely the lower left-hand corner of the boiler. As a result, steam is formed in the lower tubes, which are inclined as illustrated in the drawings and in the diagram, and, due to two distinct actions, circulation of the water in the boiler takes place. The first action is a diminution of the density of the water by expansion when heated. A second effect is a diminution of the specific gravity of the column of water due to the space taken up by steam bubbles. This causes the column of water at the left of the diagram to become of considerably less density than the comparatively cold water at the right of the diagram in the riser 2. As a consequence, the level of water in the two headers will not be the same, the column rising higher in the header 1 than in the header 2. As a result of this action, the water will tend to flow back to the riser 2, through the inclined intermediate tubes of the boiler. Of course, it is understood that, instead of a single tube taking care of all the difference in level, as illustrated dia-

grammatically in Fig. 1, there is a group of tubes which performs this function. Instead of having a definite water level in both sides, as indicated in Fig. 1, the level will vary and will be indefinable in header 1 because of the fact that violent ebullition is taking place in this header and, in fact, some of the water is cast up in the header 1 in proximity to the uppermost group of tubes. This is due to the fact that heat is applied rapidly and in great quantity along the entire length of the header and also due to the relatively small cross-sectional area of the header 1 as compared with the aggregate area of the water containing tubes which discharge heated water into this header. The water level is roughly indicated in Fig. 2 by the dotted line. It can now be seen that a circulation is provided in the lower tubes of the boiler. The water is raised by the mechanical action of expansion of the column of water and by the mechanical action of the escaping bubbles in tossing it above the normal level. Some of the water is caught in the mouths of the inclined intermediate tubes and runs back in thin sheets or streams through these intermediate tubes, which are highly heated, and not only is the steam mechanically separated by the action of the water in running down an incline in a thin stream, but such water is also flowing over a very hot metallic plate in a thin sheet with a free steaming surface in ideal condition for the rapid formation of steam. This is an action entirely foreign to all boilers of the prior art and I consider it to be broadly new and to be in fact a new method of generating steam.

It is, furthermore, a new method of circulating the water in such a way as to allow the entrained steam to be separated from the water by a mechanical sifting. This action of circulation and separation is objectionable in the structure of the boiler disclosed in my copending application No. 656,179, above referred to. In addition to the formation of steam, I am enabled by the present structure to secure two added functions, namely, a superheating action and an economizing action. The superheating action is secured by conducting a part of the hot gases up through the flue space 44 and over the top of the sections, as indicated by the arrows in Fig. 1. The upper group of tubes is thereby heated to a high temperature and, as these tubes contain substantially no water, but are filled solely with steam, it can be seen that the most favorable conditions for completely drying and superheating the steam are afforded. This is obvious when it is considered that a great number of these tubes are connected in multiple so that no considerable current of steam is formed in any one of the tubes, even under

the most rapid steaming of the boiler, but each of the tubes is heated to such a degree that it is practically impossible for any moisture to be carried from the riser 1 through any of the tubes to the steam header. I have found as a result of experiments that the superheating action in the upper part of the boiler will vary in accordance with the level of water in the boiler, if all the gases 10 are first conducted through the water tubes before impinging upon the superheating tubes. The small water tubes 3 absorb the heat so rapidly that, if the number of tubes carrying water is appreciably changed by 15 variation in the water content, a considerable amount of variation in the temperature of the gases will result. By providing the added path for the hot gases, superheating will always be accomplished regardless of 20 variations of water level.

The steam may be superheated by conducting all of the furnace gases through the water containing tubes before passing beyond the baffle, but this manner of operating 25 the boiler does not permit of so wide a range of water content as is the case when I pass a portion of the hot gases from the furnace directly to the superheating zone above. With this latter method, the boiler tends to 30 maintain a more stable and uniform temperature of the superheated steam.

An economizing action is secured by conducting the gases after they have passed through the tubes down between the baffle 35 and the rear header 2 to heat the incoming feed water. It can be seen that no direct heat from the furnace engages the lower right hand portion of the sections. The gases escape through this portion of the 40 boiler and pass to the flue 17 in contact with the header 2. Due to this arrangement of the currents of gases and to the construction of the boiler, I am enabled to exhaust the 45 gases into the stack at or even slightly below the temperature of the superheated steam, depending upon the water content of the boiler. The damper 47 may be opened or closed to a greater or less extent, as desired, to secure a proper superheating action.

50 It can be seen that I secure four actions in a single boiler structure. I secure a circulating zone, which is roughly indicated in Fig. 1. Here the water is heated to the proper temperature to form steam and 55 passes upward in the header 1 to the separating zone where the steam is mechanically separated out and the water is further heated by being projected in thin sheets with a free steaming surface over the inside 60 face of the hot tubes. Above the separating zone is a superheating zone, in which the steam is heated in the absence of any water surface, so as to produce a pure superheating action. The furnace gases, although they 65 have spent most of the heat energy are still

of sufficient temperature to be useful in heating the feed water and, by the provision of the baffle and the smoke flue, I define an economizing zone, as indicated in Fig. 1.

Let it be understood that these zones are not sharply defined and that each overlaps the other, but it is to be understood that the inability of exact definition is immaterial, as the fact is that certain definite actions take place in certain definite parts of the boiler. This boiler is capable of very heavy duty 75 and can stand heavy demands of steam without failing to perform its duty as a boiler, superheater and economizer.

The course of the water and the thermodynamic relation of the water to the fire gases may be traced as follows: The water is first introduced in the relatively cold condition at the feed connection 13. Being relatively cold, it tends to sink in the header 2 but is drawn by the circulation in the boiler into the open inclined tube adjacent the bottom of the header. Here it is subjected to the heat from the last pass of the gases and receives a quantity of heat which may be termed thermodynamically as "pre-heat." The heat that the water now receives tends to make it lighter and it moves along the lower tubes toward the front header receiving the necessary heat to bring it to the temperature of steam at the given pressure.

As insufficient heat may be imparted to it in one passage of the tubes 3, it may be returned in the circulation to the higher ones of said inclined tube 3 to the rear header 2 and again pass through the transverse tube 3 until it reaches the temperature or substantially the temperature of the steam which is carried in the boiler. In terms of thermodynamics the heat that the water contains at this point is termed the "heat of the liquid." At the same time there is a tendency to form small bubbles of steam by the excess heat that is applied after the water has reached the temperature of wet steam at the given pressure. Before the water can pass into steam at the given temperature a large quantity of heat must be supplied in order to drive the molecules apart. This heat does not raise the temperature of the water and serves merely to change the condition or state of the water from a liquid to a vapor. This heat is termed the "heat of vaporization."

The excess heat which is not required to raise the temperature of the water in the lower tubes 3 to the boiling point provides the necessary heat of vaporization to form the small steam bubbles above mentioned. The amount of steam formed is relatively small as the quantity of heat required for the heat of vaporization is relatively great. When the water has been heated to the point of formation of steam bubbles it tends to ascend in the riser 1. The additional heat 120 125 130

which it receives while in the riser expands the steam bubbles and forms additional steam bubbles. As the riser is of relatively small cross-sectional area, particularly as compared with the water containing tubes which open into it, the water is projected upward violently. This releases part of the steam bubbles and at the same time small portions of the water are cast into the open mouths of the separating tubes. These tubes are heated by the first pass of gases both from the flue 44 and from the pass up through the water tubes. This is the region where most of the steam is formed and it is here that the heat of vaporization must be supplied. I provide this heat by the first pass of the fire gases directly from the furnace and thereby secure the results of generating dry steam as distinguished from generating wet steam, as is done in prior art devices of the water circulating type. In those devices the heat of vaporization is not applied at the free water surface, as is the case in the present device, but is applied to the body of water. The result is in those devices that the steam cannot free itself from the body of water without carrying a very considerable percentage of water with it. The steam which is thus generated and freed passes up into the upper tubes where it receives further heat which is termed in thermodynamics as "superheat."

This boiler is not to be confused with the type known as the "flash boiler" as it has a very considerable water content, a highly developed system of circulation and a considerable reserve capacity. It is also not to be confused with the "water level" type of boiler, in which the heating tubes are all located on lower levels than the main water level, and from a structural standpoint it is important that this boiler be not confused with the "sectional" type of boiler in which a complete function is not entirely confined to a single section. The advantages of all these types are secured in the present invention without their disadvantages. The water is separated into small quantities exposed to the heat of the furnace and steaming is very rapid. This is the advantage which is generally secured in the flash type of boiler. The reserve capacity of the water level type is also secured. The ability of replacement of a part of the boiler, which is an advantage of the sectional type of boiler, is also secured, although this boiler does not expose a single seam or joint.

By the above construction, a boiler of maximum utility is provided. All of the sections are interchangeable and each section is of such size that it can readily and conveniently be handled by one man and the removal of a section in no wise incapacitates the rest of the boiler. The safety factor of the welded construction is greatly

in excess of any structure hitherto employed. In fact, tests made on a Riehle testing machine proved conclusively that the joint itself is the strongest portion of the boiler. Due to the reduced water content, the dead load on the boiler setting is greatly reduced and it is possible to employ this type of boiler in locations in which the ordinary boiler would be prohibited. The comparatively small water content also reduces the dangers from explosion.

I do not intend to limit the use of the above described boiler only to the production of superheating steam as I am able to change the quality of the steam by working the boiler at a different water content. By increasing the water content I am enabled to produce dry steam, or by varying the water content to any desired degree, I am enabled to produce any desired quality of steam.

Although I have described my invention in connection with a certain specific embodiment and have described in connection therewith certain details of construction, I do not mean thereby to limit myself to any specific construction, nor to any specific details, as I consider the invention to be broadly new and to be capable of being carried out by different means and in different relations than the one which I have set out, as the single embodiment that I have described has been set forth, not as a limitation, but as illustrative of my invention in an operative form as required by the statutes. I further consider the process of generating steam which is carried out in this boiler to be broadly new and intend to claim the same as such.

I claim—

1. The method of treating water to generate steam which consists in applying heat unevenly to a body of water and selectively causing the hottest portion thereof to separate by thermal action, projecting said hottest portion in a thin sheet having a free steaming surface across a flash surface and supplying heat at substantially furnace temperature to said flash surface in sufficient quantity to supply the necessary heat of vaporization to form steam from a considerable portion thereof, and returning the remainder of said heated water which is not formed into steam to said body of water.

2. The method of circulating water and forming steam in a boiler which consists in heating said water to bring a part thereof substantially to the boiling temperature and simultaneously causing another part of said water to follow a closed path of circulation within the main body of water and in causing said heated part of said water to travel from said main body with a free steaming surface over a highly heated flash surface, and supplying heat to said flash surface at

substantially furnace temperature in sufficient quantity to furnish the necessary heat of vaporization to form steam from a considerable portion thereof and moving the remainder back to said main body of water.

5. The method of forming steam which consists in heating a body of water to the point of formation of steam bubbles therein and projecting said water and steam bubbles 10 in a thin sheet with a free steaming surface over a heated flash surface to separate by mechanical action the heavier water particles from the steam bubbles and by thermal action in driving off the steam bubbles by 15 supplying heat at substantially furnace temperature through said flash surface to furnish the necessary heat of vaporization.

4. The process of generating steam which consists in heating the water to the point 20 of giving off steam, lifting a portion of said water by thermal action above the mean level of the water and causing it to run in a thin sheet having a free steaming surface down an inclined flash heating surface to a 25 lower level and supplying heat at substantially furnace temperature to said flash surface in quantity sufficient to supply the necessary heat of vaporization of a substantial part and returning the water which is not converted into steam to the main body of water.

5. The process of generating steam which consists in raising the temperature of the water to the point of giving off steam in an 30 inclosure and simultaneously causing the water in said inclosure to boil up and onto a plurality of inclined flash surfaces at different heights to cause the water to run down said surfaces in thin films or sheets having 35 free steaming surfaces, and supplying said flash surfaces with heat at substantially furnace temperature in sufficient quantities to supply the heat of vaporization for the water so boiling up to form steam.

45. 6. The process of generating steam in an inclosed space which consists in heating a main body of water to the boiling temperature and continuously bringing a small part of said water in thin sheets having free surfaces in contact with highly heated flash surfaces to form steam supplying heat at substantially furnace temperature to said flash surfaces in quantities sufficient to furnish the necessary heat of vaporization and 50 draining the remainder of said small part which is not formed into steam back into said main body.

7. A boiler comprising a pair of continuous risers adapted to be only partly filled 60 during normal operation of the boiler, a plurality of inclined tubes lying above and a plurality of inclined tubes lying below the water level, and a plurality of tubes lying between said upper tubes and said lower tubes, all of said tubes being connected at

their ends to the side walls of said risers to form a container, means to heat all of said tubes and one of said risers, said means comprising a furnace and a casing adapted to make one pass of the furnace 70 gases directly from the furnace along one side of said riser and another pass of furnace gases directly from the furnace along the other side of the riser through the tubes both above and below the water space regardless of the water level.

8. In a boiler, a plurality of units, each unit comprising a pair of wrought metal risers of different lengths, a plurality of wrought metal tubes welded to said risers to 80 form an integral unitary piece of metal, the space between the tubes being substantially uniformly greater at the longer riser than at the shorter riser, a furnace under said shorter riser, means to make the first pass 85 of the furnace gases directly upward through the tubes connecting said risers to a point above the water level and means for, conducting a portion of the furnace gases along the outside of the shorter riser to a 90 point substantially above the water level.

9. In a boiler, a pair of risers, a plurality of tubes connecting said risers, a fire box below one of said risers, a fire flue leading over said riser and down through the tubes 95 connected to said riser to form one passage for the fire gases, another passage for the fire gases being formed through the tubes connected to the lower parts of said risers, said one riser lying between and being heated 100 by the fire gases of both passages.

10. A boiler comprising a closed cellular vessel, said vessel comprising a pair of risers, tubes connecting said risers, said risers being connected solely by said tubes, 105 said boiler being adapted to operate normally with the tubes and risers only partially filled with water whereby the upper tubes contain steam and the lower tubes contain water, a furnace and flues therefor 110 to cause zones of different thermal operation in said vessel, one of said flues conducting hot gases directly from said furnace down through the steam and water tubes regardless of variation of the water level.

11. In combination, a boiler comprising an integral unitary cellular closed vessel comprising generally horizontal tubes connected at their ends by generally vertically continuous risers, said vessel being only partially filled with water, a furnace for the same, means to conduct hot furnace gases from the furnace directly over the uppermost tubes and down through said tubes, and means to guide hot furnace gases in a 120 first pass directly upward through the lowermost tubes, to produce zones of distinctly different thermal action.

12. In combination, a pair of continuous headers, tubes connecting said headers, said 130

tubes and headers lying in a single plane, part only of said tubes and headers containing water, a furnace adjacent one header, means for conducting hot furnace gases directly over the top of said one header down through all the tubes, a baffle extending from the bottom of the section up to a point adjacent the water level, and defining another course for furnace gases up through 10 part of said tubes and over said baffle.

13. In combination, a boiler comprising a pair of continuous risers and a plurality of tubes connecting said risers, one of said tubes being filled with water, another of 15 said tubes being inclined and partially filled with water and another of said tubes being at all times substantially free of water during normal operation of the boiler, a furnace adjacent one of said risers, means for 20 conducting hot furnace gases upward along the front of the adjacent riser, and means for conducting the spent furnace gases along the rear of said other riser.

14. In combination, a boiler comprising a 25 plurality of sections, each of said sections comprising a pair of risers and a plurality of tubes connecting said risers, said risers being only partially filled with water, a casing inclosing said boiler, a fire box placed 30 beneath one end of said sections and having a fire flue leading over the adjacent risers and down through the tubes, a smoke flue 35 opening in said casing adjacent the bottom of the other risers of the sections and a baffle between said fire box and said smoke flue.

15. In combination, a boiler comprising a plurality of similar sections, each of said sections comprising a pair of risers and a plurality of tubes connecting said risers, corresponding 40 risers at one end of each section being shorter than the risers at the other end, all of said risers being only partially filled with water during operation of said boiler, a casing inclosing said boiler, said 45 casing provided with a fire box and a smoke flue, the fire box being located adjacent the ends of the sections having the shorter risers, and a smoke flue opening into the casing adjacent the other ends of the sections in 50 proximity to the bottom of the longer risers, a baffle located between the fire box and smoke flue and a separate fire flue extending from the fire box to the tops of the sections over the shorter risers.

16. In combination, a boiler comprising a 55 plurality of similar sections, each of said sections comprising a pair of risers and a plurality of tubes connecting said risers, corresponding risers at one end of each section being shorter than the risers at the other end, all of said risers being only partially filled with water during operation of 60 said boiler, a casing inclosing said boiler, said casing provided with a fire box and a 65 smoke flue, the fire box being located adj-

acent the ends of the sections have the shorter risers, and a smoke flue opening into the casing adjacent the other ends of the sections in proximity to the bottom of the longer risers, a baffle located between the 70 fire box and smoke flue and a separate fire flue extending from the fire box to the tops of the sections over the shorter risers, said shorter risers forming one wall of said fire flue and said longer risers forming one wall 75 of the smoke flue.

17. A boiler comprising an integral unitary structure of interconnected risers and transverse tubes, said tubes lying at different heights, with respect to said risers, a furnace for heating said tubes and means for conducting gases at furnace temperature in one path through the upper tubes and in another path through the lower tubes, the upper tubes containing steam and the lower 85 tubes containing water in normal operation of said boiler, said two paths including between them and being defined by one of said risers.

18. In a boiler, a plurality of sections, 90 each of said sections comprising a pair of risers and a plurality of transverse tubes connecting said risers, said risers being partially filled with water, means for supporting each section, a furnace and a casing 95 surrounding said boiler, and providing fire-flue space about one end and above the top of the boiler, said fire-flue space leading directly from the furnace.

19. In a steam boiler, a plurality of sections, each section comprising a pair of risers and a plurality of tubes connecting said risers, said risers being partially filled with water during operation of the boiler, a steam header having connection with each 105 of said sections at the top of one of said risers of each section, a mud drum having an independently detachable connection, with the bottom of the said riser of each section, a feed water pipe having independently 110 detachable connection with each boiler section by a pipe connected independently to said riser of each section a substantial distance above the bottom thereof.

20. In a boiler, a plurality of sections, 115 each section comprising a pair of continuous integral risers, a plurality of tubes connecting said risers, said sections being supported by rods attached to the tops of the risers, a casing surrounding said boiler and 120 providing flue space around the ends and top of the boiler, said casing being provided with a fire box and a smoke flue, the fire box being located under one end of each of the sections and the smoke flue extending to the 125 bottom of the opposite end of each of the sections, a baffle plate between said fire box and said smoke flue, a mud drum connected to the bottom of each riser and a feed water connection to each of said sections near the 130

lower end of the riser adjacent the smoke flue.

21. In combination, a boiler comprising a pair of continuous vertical risers, a plurality of tubes joined at their ends to said risers and having unobstructed communication with each other through said risers, said boiler being adapted to operate with the level of the water substantially below the tops of said risers, a furnace below said tubes and means to conduct gases directly from said furnace upward along the front of the front risers down through all of said tubes and upward along the rear of the rear risers.

22. In a boiler a plurality of sections, each of said sections comprising a plurality of continuous wrought metal headers, a plurality of wrought metal tubes united thereto, said headers united solely by said tubes, all of said tubes being directly and integrally united to one of said headers, a part of said tubes containing water and the remainder of said tubes containing steam only, each section comprising a unitary integral piece of metal, a furnace and a vertical baffle intermediate said riser for conducting furnace gases in a first pass from the furnace to a point substantially above the surface of the water, and a flue for leading a separate pass of hot gases directly from the furnace along the front of said one header and over the top of the same.

23. In a boiler, a plurality of sections, each section comprising a plurality of continuous vertical headers of wrought metal and a plurality of wrought metal tubes connecting said headers, said tubes and headers being in a substantially vertical plane, all of said tubes being connected integrally by autogenous welding at one end thereof to one of said headers, each section comprising a unitary integral piece of metal, said one header and another of said headers being partially filled with water during normal operation of the boiler, a furnace and a vertical baffle intermediate said riser for conducting furnace gases in a first pass to a point substantially above the surface of the water in the boiler, and a flue for leading a separate pass of hot gases directly from the furnace along the front of said one header and over the top of the same.

24. In combination, a continuous vertical riser adapted to be partially filled with water during the normal operation thereof, a plurality of tubes connected to one side of said riser, both above and below the water level, a furnace below said riser and means to pass gases from said furnace directly upward through said tubes and along opposite sides of said riser, to a point substantially above the water surface therein.

25. In combination, a vertical riser adapted to be partially filled with water, a plu-

rality of transverse tubes connected one above the other upon one side of said riser, both above and below said water surface, a furnace below said riser, a casing adjacent to but spaced from said riser, a part of the furnace gases being passed directly upward between said casing and said riser and over the top of the same, another part of the gases being passed directly up to said transverse tubes on the other side of the riser and a vertical baffle, both parts of said gases being passed over the top of said baffle and down through all of said transverse tubes.

26. A method of generating steam which consists in heating a body of water unevenly to bring a portion thereof to substantially the boiling point, then projecting said heated portion vertically, then breaking said portion into a plurality of small bodies of water at different heights having free steaming surfaces, then passing said bodies into a heat zone which is maintained substantially at furnace temperatures, then draining back to the main body of water such part of said bodies as are not evaporated.

27. A boiler comprising a structure of substantially vertical tubes and substantially horizontal tubes interconnected with each other the horizontal tubes lying at different heights, a furnace under said tubes said furnace being arranged to pass hot gases direct from the fire through the horizontal tubes and a flue for conducting hot furnace gases from the fire along the vertical tubes over the same and then down through the horizontal tubes to the stack.

28. A boiler comprising a unitary structure of interconnected tubes, said tubes lying at different heights and being connected at their ends to risers, a furnace under said tubes and risers, the tubes at the lowermost height being filled normally with water, the tubes at the uppermost height being normally substantially free of water and the tubes on intermediate heights receiving the water cast up by the action of steaming and draining back to the lower tubes, and a furnace having means to make a pass of hot gases up through the water tubes and the intermediate tubes and a flue from the furnace to lead hot gases over the top of the risers and down through the steam tubes, the intermediate tubes and the water tubes.

29. In a boiler, a vessel adapted to be partially filled with water, said vessel having inclined discharge tubes connected along its side at different heights above the level of the water, said discharge tubes having an aggregate of openings greatly in excess of the cross-sectional area of said vessel, means to apply heat to said tubes and to the lateral surfaces of said vessel to cause the water in said vessel to boil up and discharge a relatively small quantity of water simulta-

neously to a plurality of said inclined tubes, said heating means comprising a furnace and a casing for causing a first pass of gases directly from the furnace through said tubes 5 to supply the necessary heat of vaporization to the water discharging therethrough and a flue leading hot gases directly from the furnace along the side walls of said vessel over the top of the vessel and down through the

tubes and a steam connection for discharging the pressure generated in said vessel.

In witness whereof, I hereunto subscribe my name this 22nd day of May, A. D. 1914.

WILLIAM H. WINSLOW.

Witnesses:

LEONARD W. NOVANDER,
JOHN A. DIRUNE.

It is hereby certified that in Letters Patent No. 1,236,641, granted August 14, 1917, upon the application of William H. Winslow, of Chicago, Illinois, for an improvement in "Steam-Boilers," an error appears in the printed specification requiring correction as follows: Page 4, lines 109-110, for the word "objectionable" read *obtainable*; and that the said Letters Patent should be read with this correction therein that the same may conform to the record of the case in the Patent Office.

Signed and sealed this 18th day of September, A. D., 1917.

[SEAL.]

R. F. WHITEHEAD.

Acting Commissioner of Patents.

CL. 122 200.
